UNITED STATES PATENT OFFICE.

ROGER J. BOYD, OF CHICAGO, ILLINOIS, ASSIGNOR, BY MESNE ASSIGNMENTS, TO
CARSON PIRIE SCOTT & COMPANY, OF CHICAGO, ILLINOIS, A CORPORATION OF
ILLINOIS.

SHIPPING-CASE.

1,351,740.

Specification of Letters Patent. Patented Sept. 7, 1920.

Application filed August 22, 1917. Serial No. 187,642.

To all whom it may concern:

Be it known that I, ROGER J. BOYD, a citizen of the United States, residing at Chicago, in the county of Cook and State of Illinois, have invented certain new and useful Improvements in Shipping-Cases, of which the following is a specification.

This invention relates to improvements in packing boxes.

10 The primary object of the invention is to provide a packing case in which glasses may be safely packed for shipment, or delivery, in which such construction is embodied as will securely retain the glasses in position 15 in the box or case, maintaining them in definite, separated positions, and preventing contact with the sides, ends and top of the box, and between the glasses.

Other objects and advantages of the invention will become apparent in the course of 20 the following description.

I prefer to make the boxes or cases of heavy paper, strawboard, or the like, since the material has, for these purposes, come 25 into very general use, and are found to meet satisfactorily, the exigencies and conditions of packing and shipping.

In the drawings—

Figure 1 is a perspective view of the box 30 with the top flaps thrown back, to show the formation of the tray showing the drinking glasses therein.

Fig. 2 is a perspective view of the tray removed from the case.

35 Fig. 3 is a vertical transverse sectional view showing the retaining sections holding the glasses.

Referring now to the drawings, the numeral 1 represents the box or case, which is 40 of a rectangular form and comprises the ends 2, sides 3, bottom 4, and end flaps 5, and side flaps 6, which flaps form the cover or top of the box, all of which is of the usual construction, and the flaps are held closed by adhesive strips.

Placed in the bottom of the box is a retaining or cushioning section 7, which comprises a top 8 having the side and end flaps 9 45 extending downwardly, whereby it is supported some distance above the bottom 4 of the box, and said section being of a contour corresponding to that of the box. The glass holding tray 9' consists of the main body portion 10, having end flaps 11 and side flaps

12, which extend downwardly and rest upon 55 the section 7 or could extend downwardly between said section and the sides of the box. By this structure, it is seen that the tray can be supported a proper distance above the section to properly hold the glasses, as will be 60 hereinafter more fully described.

The top 10 of the tray 9' is provided with a series of openings 13 of a size to receive the glasses when laid on the side, and each opening, at one end, is provided with an inwardly extending tongue 14, formed integral with the top 10. As shown in Fig. 1 of the drawings, the tongue extends into the glass and holds it against movement during transportation. Within the box, above the tray 70 is placed a retaining or cushioning section 14', which comprises a bottom 15, sides and ends 16 and 17, and constructed in precisely the same manner as the section 7, but is placed in the box in an inverted position, just 75 the opposite from that of the section 7. The bottom 15 of this cushioning section 14' is provided with an elongated hole, through which the fingers may be passed, for removing the section out of the box. 80

In packing the glasses, the cushioning or retaining section 7 is first placed in the bottom of the box, and the glass holding tray placed therein, with the ends and sides 11 and 12 resting upon the top of the section 7. 85 The glasses are then placed in the openings 13, with the tongues 14 entering the glasses, whereby they are held firmly within the opening. If the glasses are very small, the ends and the sides 11 and 12 of the tray, are 90 forced downwardly between the sides of the section 7 and the sides of the box, so that the glasses in resting upon the section 7, will assume a horizontal position. The retaining or cushioning section 14' is then placed in 95 the box, with the bottom 15 resting on the glasses, thus firmly holding the same against vertical movement. The closing flaps of the box are then folded over upon the sides and ends of the upper retaining section to prevent any vertical movement thereof, thus firmly holding the glasses in position. 100

Having thus described my invention, what I claim is:—

The combination with a box, of a cushioning section in the bottom of the box, a tray formed of a top, sides and ends, said sides and ends resting on the cushioning section, 105

the top of the tray having elongated openings, tongues formed integral with the top and extending inwardly from one end of the openings and adapted to enter the glasses within the openings, and a cushioning section above the tray and resting upon the glasses.

In testimony whereof I affix my signature in presence of two witnesses.

ROGER J. BOYD.
